Primary Examiner — Amy C Wierenga

CLAIM

The ornamental design for a shower drain mesh strainer sticker, as shown and described.

DESCRIPTION

FIG. 1 is a front perspective view of a shower drain mesh strainer sticker of the present invention.

FIG. 2 is a front side view of FIG. 1.

FIG. 3 is a back side view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1; and,

FIG. 8 is a back perspective view of FIG. 1.

The broken lines shown in FIG. 1-8 illustrate environment only and form no part of the claimed design.

1 Claim, 8 Drawing Sheets
